CLAIM

The ornamental design for a clamp for storm sashes, screens or the like, as shown.

DESCRIPTION

FIG. 1 is a perspective view taken from the top, rear and left side of a clamp for storm sashes, screens or the like showing my new design;

FIG. 2 is a top-plan view thereof;

FIG. 3 is a rear elevational view thereof;

FIG. 4 is a right side elevational view thereof, the left side being a mirror image thereof;

FIG. 5 is a front elevational view thereof;

FIG. 6 is a bottom view thereof.
